UNITED STATES PATENT OFFICE.

MATHIAS KAMMERER AND JOHN M. KAMMERER, OF EL PASO, ILLINOIS, ASSIGNEES
OF ONE-HALF TO ARTHUR HENNING AND JOHN F. SCHOFIELD, BOTH OF EL PASO,
ILLINOIS.

CULVERT.

1,412,616.

Specification of Letters Patent. Patented Apr. 11, 1922.

Application filed July 27, 1921. Serial No. 487,903.

To all whom it may concern:

Be it known that we, MATHIAS KAMMERER and JOHN M. KAMMERER, citizens of the United States, residing at El Paso, in the 5 county of Woodford and State of Illinois, have invented certain new and useful Improvements in Culverts, of which the following is a specification.

This invention relates to new and useful 10 improvements in culverts of the type consisting of molded sections which may be easily assembled to provide a finished culvert possessing many advantages, other than the desirable characteristics of a culvert constructed entirely on the site where the same 15 is to be located.

An important object of the invention is to provide molded arched sections and floor 20 sections, and means for securely locking the sections constituting the culvert together.

Another object of the invention is to provide a culvert consisting of a plurality of ready molded sections which after being assembled in their relative places are united 25 or made into an integral structure by concrete being poured at certain places in the culvert.

A further object of the invention resides in 30 the provision of an arrangement of tie-rods for the various sections of the culvert whereby all possibility of any relative movement between the sections is precluded thereby providing a culvert which is practically a one piece structure.

A still further object of the invention is 35 to provide a culvert of the above named type which is so constructed as to preclude any possibility of the structure settling after it has been installed.

Still another object of the invention resides in the provision of a simple and effective means for anchoring the head walls of the culvert and interlocking them with other parts of the culvert.

A further object of the invention is to provide a culvert possessing the features above set forth which is exceedingly simple and durable and may be installed in the minimum of time.

Other objects and advantages of the invention will become apparent during the course of the following description.

In the accompanying drawings forming a part of the specification and wherein like

numerals are employed to designate like parts throughout the several views,

Figure 1 is a side elevation of a completed culvert embodying our invention.

Figure 2 is a similar view showing a part thereof in section. 60

Figure 3 is a transverse section through the culvert.

Figure 4 is a perspective view of one of the arched sections illustrating the reinforcing and anchoring means associated therewith. 65

Figure 5 is a perspective view of a floor section or slab embodying our improvements,

Figure 6 is a side elevation of a portion of a culvert showing a modified means of 70 interlocking and anchoring the various sections,

Figure 7 is an enlarged transverse section of the same,

Figure 8 is a top plan of a modified form 75 of floor section,

Figure 9 is an enlarged perspective view of an arch section embodying a modified form of reinforcing and anchoring means,

Figure 10 is a perspective view of one of 80 the head walls of the culvert illustrating the anchor and reinforcing means therefor.

Figure 11 is a perspective view of a part of a modified form of floor section.

Figure 12 is a top plan of the culvert 85 embodying the modified sections.

Figure 13 is a fragmentary side elevation of a culvert embodying a slightly modified form of anchoring means.

In the drawings wherein for the purpose 90 of illustration we have shown the preferred embodiments of our invention, the numeral 15 designates the floor or base of the culvert which consists of a plurality of molded sections 16 adapted to be supported by a suitable foundation and which may be positioned in a trench if desired. These sections are preferably molded from concrete and each consists of a substantially rectangular slab, the intermediate ones in the culvert 95 each having one transverse end provided with a horizontal groove 17 extending the entire width thereof, while the opposite transverse abutting end is provided with a transversely extending tongue or rib 18 100 adapted to fit the groove 17 of the adjacent floor section 16. This interlocking feature 105 between the floor sections is only provided

upon the inner transverse ends of the end sections in the culvert for obvious reasons.

Each floor section 16 along its longitudinal edges is provided with upstanding walls

- 5 19 which extend a substantial distance above the top face of the section. Rising from the upper face of the section are a pair of spaced similar walls or ribs 20, each being spaced from its adjacent wall 19 to provide each floor section with a trough 21 extending longitudinally of the section adjacent each longitudinal side edge thereof. The top surface of the ribs or shoulders 20 are preferably flat and arranged in a plane parallel to the top 10 surface of the floor section. The inner longitudinal edges of the ribs are rounded off to merge into the top face of the section to form a channel 22 arranged longitudinally and centrally of the section.
- 15 In the trough 21 of each floor section, as shown in Figure 5, a tie rod 23 is provided to extend longitudinally of the trough. In the present modification, each tie rod consists of an inverted U-shaped member having its ends depending to be embedded in the bottom of the trough. As clearly seen, the elongated bridge portion of each tie rod is spaced above the bottom of the trough and is arranged in a plane approximately parallel to the plane of the top surfaces of the ribs 19 and 20. These tie rods are preferably disposed equi-distant from the side walls of its trough. It is to be understood that we do not limit ourselves to the specific 20 manner of anchoring the tie rods to the various sections, as innumerable ways of securing the tie rods to the sections may be resorted to without departing from the spirit of the invention.

- 25 40 The floor sections are assembled by positioning the various sections upon their foundation and alining them so that the ribs 19 and 20 are longitudinally alined and the tongue 18 of one section fits in its groove 17 of the adjacent section. When the sections are assembled in this manner, it will be obvious that a trough 21 is arranged adjacent each longitudinal side of the structure formed and extends from one end of the culvert to the other.

- 45 50 As clearly seen in Figures 2, 3 and 4, each arch section 24 consists of a roof portion having side walls depending therefrom in spaced parallel relation, and it is to be understood that the arch sections need not be of arched configuration but may be of any other shape desired. As best appreciated from Figure 3, the distance between the inner surfaces of the sides of the arch section 55 is less than the distance between the outer surfaces of the ribs 20 so that when the arch sections are positioned upon the floor sections, the bottoms of the arches will be supported upon the ribs 20 as at 25, and the 60 outer surfaces of the lower ends of the arch

sections will be spaced inwardly from the inner faces of the walls 19 of the troughs, for a purpose which will be presently described.

Depending from the under face of each 70 side wall of each arch section 24 is a preferably U-shaped tie rod 27 which extends longitudinally of the section, the vertical ends 28 of which are embedded in the walls of the arch section. As seen in Figure 1, an 75 end wall 29 is provided for each end of the culvert and is molded from concrete the same as the other sections of the culvert. The lower ends of these end walls are also adapted to be supported upon the ribs 20 80 of the floor sections in the same manner as the arch section and each end wall is provided at each side with an outwardly and downwardly inclined brace portion 30 as clearly shown. A U-shaped tie rod 31 depends from the under face of each leg of the end wall the same as the tie rod of the arch section.

85 After the floor sections 16 have been assembled in the manner outlined herein, the arch sections 24 are positioned thereon in the manner herein stated so that the meeting or abutting end of the arch sections are disposed approximately halfway between the abutting ends of the floor sections as clearly 90 shown in Figure 1. The end walls 29 are positioned upon the end floor sections at each end of the culvert in a manner well understood. When the various sections are assembled in this manner, the tie rods of the 95 arch sections and end walls depend into the troughs 21 provided by the floor sections and are arranged between the tie rods 23 of the floor sections and the outer faces of the ribs 20, as clearly shown in Figure 3. Freshly 100 mixed concrete 32 is then poured into the troughs 21 between the outsides of the arch sections and the upstanding walls 19 of the floor sections. This concrete is then tamped around the tie rods and after it has set, it 105 will be seen that all of the sections of the culvert will be interlocked and firmly bound together. Due to the fact that the floor sections span the meeting edges of the arch sections it will be seen that the tie rods of 110 the floor sections will lap the joints of the arch sections and the tie rods of the arch sections will lap the meeting edges of the floor sections as clearly seen in Figure 2.

115 A slightly modified form of floor section 120 and arrangement of tie rods is shown in Figures 6, 7 and 8, the floor sections each consisting of a molded concrete slab 33 having a longitudinally extending shoulder 34 (best seen in Fig. 7) adjacent each longitudinal edge and the top face of the slab. A U-shaped tie rod 34 has its ends 35 embedded in the longitudinal sides of the floor slab so that the rod will extend laterally of the section and be disposed so that its ends and 125 130

body portion will be arranged in a horizontal plane. The arch sections for this form of floor section are the same as the arch sections for the preceding form and will therefore be designated by the numeral 24. The tie rods for the arch sections are associated therewith in the same manner as the tie rods 27 are with the arch sections 24 and depend from the underfaces of the side walls as clearly seen in Figures 6 and 7. These tie rods are designated by the numerals 27' and their intermediate portions 36 are offset upwardly of the arch sections as clearly shown in Figure 6 so that when the arch sections are assembled with the floor sections, the ends of each tie rod 27' will be disposed between the tie rods 34 of adjacent floor sections and the sides of said sections. The ends of the tie rods 27' will also be disposed below the tie rods 34 of the floor sections, while the intermediate portions 36 of the arch rods will be disposed above the tie rods 34 and will lap the meeting ends of adjacent floor sections. In this modification of the invention, a trench in the ground would be provided to receive the floor sections 33 so that a trough would be provided at each side of the assembled floor section whereby freshly mixed concrete could be poured into the troughs and tamped around the tie rods to interlock the sections. However, it will be obvious that the same type of floor section as shown in Figure 5 may be used in conjunction with this embodiment of the invention, in which case the tie rods 34 would extend laterally from the ribs 20 into the troughs and the arch sections would be supported upon the ribs 20 as hereinbefore set forth so that spaces of sufficient width for the pouring of concrete into the troughs would be provided.

In Figures 9, 10, 11 and 12 another embodiment of our invention is illustrated wherein we employ a different form of anchoring or tie means for the various sections. Each floor section 16 has its troughs provided with upstanding rods 37 the lower ends of which are embedded in the bottoms of the troughs. It is to be understood that these rods may be provided anywhere in the troughs and furthermore, may constitute the free end or ends of U-shaped tie rods which are embedded in the floor sections. The tie rods 38 for the arch sections are substantially U-shaped, the free ends 39 thereof being embedded in the underfaces of the side walls of the arch sections as clearly shown in Figure 9. However, these free ends 39 are bent where they enter the section so that the arms 60 of the tie rods extend outwardly of the side walls of the arch section and slightly beyond the same as clearly shown. This construction causes the bridge portions of the tie rods 38 to be disposed laterally of the side walls of the arch sections and in approxi-

mately the same plane with the underfaces of the side walls, although we do not limit ourselves to this specific arrangement.

The tie rods 40 of the end walls 29 of the culvert are also substantially U-shaped as clearly seen in Figure 10, the arched portions 41 of these rods being extended inwardly of the culvert and laterally of the rear faces of the end wall. These tie rods, like those of the arch sections shown in Figure 9 are preferably disposed in approximately the same plane of the underfaces of the end walls. The arms 42 of these tie rods are arranged in spaced parallel relation and at their free ends are bent to be embedded in the under faces of the end wall. In the present instance one arm 42 of each tie rod is longer than the other so that the ends of these arms may extend into the end walls at different points to reinforce the structure.

The various sections of this embodiment of the invention are assembled in the same manner as the sections in the preceding embodiment, so that the tie rods of the arch sections and end walls are disposed within the troughs 21 of the floor sections and the rods 37 of the latter pass through the loops of the tie rods as best seen in Figure 12. The rods 37 are then bent to overlap the tie rods 38 and 40, after which concrete is poured into the troughs to cover the tie rods and thereby anchor the sections together.

Slightly different arrangements of tie means are shown in Figures 13 and 14, the tie rods 38 of the arched sections 24, in Figure 13 being the same as the rod 38 shown in Figure 9. The tie rods 43 for the floor sections 16 are of substantially U-shaped configuration, the free ends 44 of the rods being embedded in the longitudinal sides of the floor sections and extended first laterally of the sides then downwardly thereof. When assembled, the tie rods 38 of the arch sections will be arranged beyond the arms 44 of the tie rods 43 and slightly thereabove as clearly shown in Figure 13.

The foregoing description and accompanying drawings have reference to what might be considered to be the approved or preferred form of our invention. We desire it to be understood that we may make such changes in the construction, combination and arrangement of parts, material, dimensions, etc., as may prove expedient and fall within the scope of the appended claims.

Having thus described our invention what we claim as new and desire to secure by Letters Patent, is:

1. A culvert structure, comprising a plurality of abutting molded base sections, the transverse meeting ends of adjacent sections provided with complementary locking means and each base section provided

- with marginal longitudinal troughs, a plurality of abutting arched roof sections the meeting adjacent ends of which are located intermediate the ends of said base sections, 5 the width of said roof sections being less than the width of said base sections, tie rods embedded in the opposite walls of each roof section, each tie rod formed with a bridge portion bent laterally of the side 10 wall of its section and disposed longitudinally thereof, tie rods disposed in the troughs of said base sections and positively interlocked with the tie rods of said roof sections by being inserted through the 15 bridge portions of said first mentioned tie rods and bent approximately at right angles, and a binding material in said trough for cementing said sections together.
2. A culvert structure, comprising a plurality of molded base sections provided with troughs extending longitudinally thereof adjacent their side edges, a plurality of molded roof sections, tie rods embedded in the opposite walls of each roof section, 20 each tie rod formed with a bridge portion bent laterally of the side wall of its section and disposed longitudinally thereof, tie rods disposed in the troughs of said base sections and positively interlocked with the 25 tie rods of said roof sections by being inserted through the bridge portions of said 30

first-mentioned tie rods and bent approximately at right angles, and a binding material in said troughs for cementing said sections together. 35

3. A culvert structure, comprising a plurality of molded base sections provided with troughs extending longitudinally thereof adjacent their side edges, a plurality of molded roof sections, tie rods embedded 40 in said base sections and located within said troughs, tie rods embedded in the opposite walls of said roof sections and arranged staggeredly with respect to the tie rods in said base sections and to coat therewith, 45 and a binding material in said troughs for cementing said sections and tie rods together.

4. A roof section for a culvert comprising an arched member of plastic material 50 molded into form, and tie rods for said section embedded in the opposite walls thereof, each tie rod formed with a bridge portion bent laterally of the side wall and disposed longitudinally thereof. 55

In testimony whereof we affix our signatures in presence of two witnesses.

MATHIAS KAMMERER.
